Primary Examiner — Gino Colan(74) *Attorney, Agent, or Firm* — Brinks Gilson & Lione(57) **CLAIM**

We claim the ornamental design for a cart, as shown and described.

DESCRIPTION

FIG. 1 is a top perspective view of a cart showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.

The broken lines in FIGS. 1-7 illustrate environmental features that form no part of the claimed design. The cart is shown with symbolic breaks. The appearance of any portions of the cart between the break lines forms no part of the claimed design.
